UNITED STATES PATENT OFFICE.

JOHN W. BLISS AND JOHN C. ERWIN, OF ELKHART, INDIANA.

MACHINE FOR WAXING OR COATING PAPER.

SPECIFICATION forming part of Letters Patent No. 513,030, dated January 16, 1894.

Application filed July 23, 1892. Serial No. 441,078. (No model.)

To all whom it may concern:

Be it known that we, JOHN W. BLISS and JOHN C. ERWIN, citizens of the United States, residing at Elkhart, in the county of Elkhart 5 and State of Indiana, have invented new and useful Improvements in Machines for Waxing or Coating Paper or other Fabrics, of which the following is a specification.

Our invention relates to the improved mechanism or apparatus for applying the wax or other substance used, to paper or other fabric, pressing and calendering the web of fabric under treatment, and automatically detecting holes or broken places in the web of 15 paper, and preventing such broken and unmarketable portions from receiving wax or other substance, by severing the web, the object being to provide a combination of mechanism into one machine that will accomplish 20 these results in the most rapid and economical manner.

We attain our object by the apparatus illustrated in the accompanying drawings, in which—

25 Figure 1 is a vertical, side elevation of the machine. Fig. 2 is a vertical sectional, front elevation of a portion of the machine. Fig. 3 is a top view of a portion of the machine, and Figs. 4, 5, 6 and 7 represent separate parts 30 or portions of the machine, referred to but not clearly shown in Figs. 1, 2 and 3.

Similar letters refer to similar parts throughout the several views.

Referring to the drawings:—A A, B B, and 35 C C, constitute the frames or supports on each side of the machine.

Paraffine wax, or other material to be used, is prepared in a suitable receptacle or tank, conveniently located, from which it is drawn 40 into the vat or pan F in which the hollow roll G is located with one third or more of its diameter submerged in the wax or material. When using material requiring heat, steam is conveyed into the roll through steam pipe 45 E. The depth to which the roll G is submerged in the substance in the vat or pan, and the shape of the latter conforming to the surface of the roll, enables us to maintain the wax or material at a uniform consistency and 50 temperature throughout the entire mass. The paper or other fabric N as it passes from the machine on which it has been made, or from

rolls, reels or spools on which it may have been wound, is passed through the machine in the direction shown by the arrows, between carrying rolls D D, under knife Z, between rolls G and H and between carrying rolls D' D', and from thence disposed of as desired. When the balance weight M is in the position shown in the drawings, roll H is suspended at a sufficient distance above roll G to enable the operator to readily pass the fabric between the rolls until it is caught between the carrying rolls D' D'. Then by means of the connections between roll H and 65 the hand wheel K—to the latter of which is attached the balance weight M which can be moved to any point on the rim of the wheel desired and fastened by set screw—roll H is lowered by turning the wheel in the direction 70 shown by the arrow until the balance weight M has reached a point past the center at the top as shown by the dotted lines M'. By this operation roll H as it descends bears the fabric down as shown by the dotted line to the 75 surface of roll G where it receives the wax or other substance on the under side of the web. The weight of roll H together with that of the balance weight M' exerts a pressure on the fabric between the two rolls, removing any 80 surplus wax or material from the fabric, thus smoothing and calendering its surfaces. The hand wheel K and the eccentrics J J, are keyed to the shaft L. The straps around the eccentrics and the journal boxes b'b in which 85 roll H operates are so constructed as to receive the ends of the connecting rods I I which are provided with right and left threads. Thus by turning the hand wheel K, roll H is either raised or lowered and by turning the 90 connecting rods I I, the distance between the eccentrics and the journal boxes is either increased or diminished, to adjust the machine to any thickness of fabric between the rolls 95 G and H. Power is applied to the shaft of roll G at the back side of the machine, either by gearing, or by belt and pulleys and transmitted from the shaft of roll G to the shaft of roll H either by belts, pulleys and counter shaft, or preferably by a pair of toothed 100 wheels O O. Shown by Fig. 7. These wheels are of peculiar pattern, their teeth extending to an edge about one inch beyond their pitch lines, and the surfaces of the rolls respect-

ively which prevents their riding as well as causes them to drop into their proper working position, equalizing the speed of the rolls previous to their surfaces coming together 5 on the fabric between them, thus avoiding any strain on the fabric. Should the web of paper, passing into the machine contain broken or unmarketable paper by reason of holes or broken places, such imperfections 10 are detected by the drags or triggers Y which hang loosely by their upper ends from the pins f on disks U, while their lower ends rest lightly on the upper surface of the fabric in front of carrying rolls D D. The drags or 15 triggers Y, pins f and disks or cams U may be of any number required, and any one of the drags dropping through such imperfections in the web, the pin or tooth on the under side of it is caught by the corrugated roll t which being in motion draws the trigger forward 20 until the tooth passes out of connection with the roll t. This action throws forward the arm W, bearing the adjustable weight X while lever T is thrown backward and by the 25 connection of said lever through rod S with the upper end of angle arm R the knife Z, operating in slots in the lower end of the angle arm, and in frames C C is brought down, severing the web and preventing such unmarketable portion of the fabric from passing 30 to or between the rolls G and H and being uselessly treated with wax or material. The positions of the various parts involved in this last operation are shown by the dotted

lines in Fig. 1. The drags or triggers Y and 35 their connections are reset by means of a handle or crank on lever T, the latter also the cams U, and arm W being keyed to shaft V.

We are aware that prior to our invention 40 vats or troughs, and heated and other rolls have been used in various forms and ways in machines for waxing and coating paper and other fabrics. We therefore do not claim the use of such broadly; but 45

What we do claim as our invention, and desire to secure by Letters Patent, is—

1. In a machine for waxing or coating paper or other fabrics the combination of the vat or pan F with the hollow roll G, carrying rolls 50 D D, and D' D' adjustable or movable pressure and calender roll H, toothed wheels O O, journal boxes b b, connecting rods I I, eccentricities J J, shaft L, hand wheel K, and adjustable or movable balance weight M, substantially as set forth.

2. In a machine for waxing or coating paper or other fabrics, the combination of shaft V, with arm W, adjustable weight X, disks or flanges U, pins f, drags or triggers Y, with 55 teeth or pins on their under side, corrugated rod t, rod S, angle arm R and knife Z, substantially as set forth.

JOHN W. BLISS.
JOHN C. ERWIN.
